UNITED STATES PATENT OFFICE.

WALTER IRA TRENCH AND ARTIMUS G. ZEPP, OF BALTIMORE, MARYLAND.

BALLAST-CLEANER.

1,074,142.

Specification of Letters Patent. Patented Sept. 30, 1913.

Application filed April 24, 1912. Serial No. 692,998.

To all whom it may concern:

Be it known that we, WALTER IRA TRENCH and ARTIMUS G. ZEPP, citizens of the United States of America, residing at the city of 5 Baltimore, State of Maryland, have invented certain new and useful Improvements in Ballast-Cleaners, of which the following is a specification.

This invention relates to a ballast cleaner. 10 Where stone ballast is used on railroad tracks, it is necessary to clean it from time to time, separating the dirt from the stone. The cleaned ballast is returned to the road-bed and the dirt deposited on the shoulders 15 of the fills to widen the embankment. In the past this work has been done with ballast forks, the dirt being shaken out from the stone, shoveled into hand barrows and carried away to be dumped on the fills as 20 described. The ballast is cleaned in order to afford the necessary drainage, as the road-bed which is not drained, cannot be kept in good condition.

The object of our invention is to cheapen 25 the laborious and expensive ballast-cleaning operation.

To this end we have provided a cleaner which consists of a screen particularly adapted for use in connection with stone 30 ballast, and means for supporting the screen so that the cleaned ballast is deposited in the desired position on the road-bed and the dirt is delivered to a wheelbarrow or other suitable receptacle by means of 35 which it may be conveyed to the slopes of the fills to be dumped. The screen is preferably of a type having an inclined net upon the upper portion of which the material to be separated is thrown, the separation or 40 cleaning taking place as the material rolls down the net.

The device, in its preferred form, is convertible and may be used either at the side of the track or in the center ditch of a 45 double-track road. However, it is not necessarily convertible and may be made solely for use in either position within the scope of our invention. When used at the side of the track, the screen is placed with its plane of 50 inclination at an angle to the rails, the net being inclined downward toward the track, so that the screened material is delivered adjacent the ends of the ties. To support the screen in this position, it is provided 55 with a foot at its lower or front end

to rest on the ties outside the rail. This foot is preferably provided with a transverse runner to engage the ties and facilitate moving the screen along the road. The upper or rear end of the screen may be supported by any suitable means as the adjustable standards which we have shown. In the preferred form of the device we also provide guides to engage the rail and determine the position of the screen. The foot, in the 60 convertible type, is made removable, and another foot, as hereinafter described, is provided for use in the ditch between the tracks.

As the machine is of a considerable length 70 in the direction of the plane of inclination of the screen, this length being greater than the distance which ordinarily separates the tracks, we find it desirable, in order not to obstruct either track when the screen is used 75 in the central ditch, to place it with its length, *i. e.*, the plane of inclination, in the direction of the track, *i. e.*, parallel to the rails. Further, to the same end and in order that it may be easily moved along the track, we 80 prefer to make it of an extreme width not exceeding the distance between the adjacent ends of the ties.

When the machine is used at the side of the road-bed, the material is shoveled up 85 about the front of the screen and thrown on the inclined net in the usual manner, but when the machine is used between the rails, in order to be used effectively it is moved backward step by step the cleaned material 90 being deposited at its front end and the material to be cleaned being shoveled up at the rear. Under these circumstances it is most convenient to feed the material into the screen from the upper and rear end. For 95 this purpose the screen, when used between the rails, is preferably adjusted at a less steep angle, so the top will not be too high for shoveling, and a hood, hopper or shield is provided to arrest the material and deflect 100 it downward upon the screen. This hopper or hood is pivotally mounted adjacent the top end, and when the screen is used at the side, it is swung over the top end, forming a rear stop to prevent the material, thrown from the front of the screen, from passing over its top edge.

In the accompanying drawings we have shown a screen constructed in accordance 105 with the principles of our invention in con- 110

nection with so much of a road-bed as is necessary to illustrate the operation of the device.

Figure 1 is a longitudinal, vertical section 5 through the screen and road-bed having a single track, the supports being shown in elevation. This shows the screen used at the side of the track. Fig. 2 is a section through the screen and trough taken on the line 2, 2 10 of Fig. 1. Fig. 3 is a front elevation of the top end of the screen taken at right angles to Fig. 1. Fig. 4 is a section on the line 4, 4 15 of Fig. 1 showing the runner and foot or support adapted to engage the ties when the screen is used at the side of the road or outside of the outer track. Fig. 5 is a vertical, longitudinal section through the screen and road-bed, the screen being placed in the central ditch. Fig. 6 is a transverse section 20 through the road-bed, certain portions being broken away, the cleaner or screen being shown in front elevation.

Referring to the drawings, the separator consists of an inclined screen 1 having a support 25 at the front consisting of feet 2 with upright legs 3 secured to the front end of the screen, and a support at the rear consisting of upright standards 4 adjustably secured to the frame of the screen by means of 30 pivoted sleeves 5. These are adapted to slide along the standards and are held in adjusted position by pins 5'. The standards 4 have feet 6; and the front feet 2 are provided with runners 7 to engage the ties. 35 Each foot 2 has a forward extension 8 forming a guide to engage the outside rail 9 and determine the position of the screen. Underlying the screen and secured thereto in any suitable manner, in this case forming 40 part of the frame, is a trough 10 having an opening 11 near the bottom for the escape of the separated dirt. This opening 11 may be closed when desired by means of a trap door 12 having a hinge 13 at its lower edge. By 45 means of this door the opening in the trough is closed to prevent escape of the dirt when the receptacle is removed for the purpose of dumping a load. The screen, as described, is used at the side of the track, the runners 7 50 resting on the ties beyond the outer rail 4, the guides 8 bearing against the rail. The cleaner, when used at the side, is moved along the rail, the runner sliding over the ties, the material being thrown from the 55 front on to the screen, and the cleaned ballast deposited around the ends of the ties.

The legs 3 with the feet 2 acting as supports for the front or lower end of the screen, are removably secured to the screen by any 60 convenient means as bolts 14, and for use as a support for the lower end of the screen or cleaner when operated between the tracks in the ditch, as shown in Figs. 5 and 6, we have provided a short foot 15 with a leg 16. This 65 is necessary as the front foot in this case

rests on the bottom of the ditch and is covered by the deposited stone, and the long foot 2 with the runner 7, if used in this position, would be held by the stone and the ties so that moving the screen along the road 70 would be difficult.

It will be noted that when the screen is used in the central ditch, the machine being moved to the rear step by step, the material is shoveled up from the rear, thrown over 75 the top of the screen, and the cleaned ballast deposited in front. As shown in Figs. 5 and 6, its angle of inclination is less steep than when used at the side of the track as in Fig. 1, the sleeves 5 being given a lower adjustment on the uprights 4. Also in this position the door 12 is removed, as it would be in the way of the workmen in shoveling the material from the rear cleaner and throwing it on the screen. To this end the hinges 13 80 are made with a partly closed hook 17 from which the pin may be easily removed.

As has been previously set forth, when the screen is used at the side of the road, as shown in Fig. 1, the material is shoveled 90 from the front of the screen after the usual manner of using an inclined screen. To prevent the material from being thrown over the end of the screen, we have provided a hood 18. This is pivotally mounted at 95 the upper end of the screen frame and adapted to be swung forward, as shown in Fig. 5, to form a hopper or guide for the material introduced from the rear over the top of the screen when working in the central trench between the tracks.

In Fig. 1 we have shown a wheelbarrow beneath the opening 11 to receive the dirt and dump it on the side of the fills. In Fig. 5 we have shown handbarrows for the same 105 purpose, as this method of transportation is more convenient when the dirt must be carried over the rails.

It will be apparent that the machine which we have described is adapted to be 110 conveniently placed to deposit a large part of the cleaned ballast where desired. The remainder of the ballast is so delivered that it may be easily thrown into the position which it is to take. The cleaner may be 115 used both at the side of the road and between the tracks, and when used in either position, may be easily moved along the road so that a party supplied with the machines may move conveniently from end to 120 end of a given piece of track and clean the ballast throughout its length at predetermined intervals.

We have thus described our invention in detail in order that its nature and operation 125 may be clearly understood. However, the specific terms herein are used in their descriptive rather than in their limiting sense and the scope of the invention is defined in the claims.

We claim—

1. A railroad ballast cleaner consisting of an inclined trough screen, a support at each end of the screen, the support at the lower end having a runner to rest and travel on the ties, the runner being placed forward from the base of the screen so it spaces the base of the screen well back from the rails whereby the material which rolls down the screen is deposited at the side of the rails.
2. A railroad ballast cleaner consisting of an inclined trough screen, a support at each end of the screen, the support at the lower end having a runner to travel on the ties and a guide to engage the rails, the guide being spaced forward from the screen so that it gives a space between the screen and the rail whereby the material is deposited at the side of the rail.
3. A railroad ballast cleaner consisting of an inclined trough screen, means for adjusting the height of the support at the upper end of the screen, a support at each end of the screen, the support at the lower end having a guide to engage the rails, the guide being spaced well forward of the base of the screen so that the material is deposited at the side of the rail.
4. A railroad ballast cleaner consisting of an inclined trough screen, supporting means therefor, and a guide to engage the rail, the guide being spaced well forward from the base of the screen.

5. A railroad ballast cleaner consisting of an inclined trough screen, means for supporting it, and a hood pivotally mounted to take a position closing the top end of the screen or to swing from that position through an arc of about 180° to a position in which it acts as a hopper or funnel when the material is introduced at the top end of the screen.

6. A railroad ballast cleaner consisting of an inclined trough screen, means for supporting it, and a pivotally mounted hood at the upper end of the screen.

7. A railroad ballast cleaner consisting of an inclined trough screen and supporting means therefor at both ends, the rear support being adjustable to vary the angle of the screen, and a pivoted deflector hood at the top of the screen adapted to close the upper end of the trough in one position to prevent material projected on the screen horizontally from going over the top, and in the other position, to act as a deflector to catch and guide to the screen, material fed from the rear.

Signed by us at Baltimore this 23d day of April 1912.
